UNITED STATES PATENT OFFICE.

CHARLES A. ELIGH, OF DETROIT, MICHIGAN, ASSIGNOR TO LONG MANUFACTURING COMPANY, OF DETROIT, MICHIGAN, A CORPORATION OF MICHIGAN.

METHOD AND MACHINE FOR MAKING RADIATOR-TUBES.

1,379,006.

Specification of Letters Patent. Patented May 24, 1921.

Application filed June 28, 1915, Serial No. 36,651. Renewed April 1, 1920. Serial No. 370,533.

To all whom it may concern:

Be it known that I, CHARLES A. ELIGH, a citizen of the United States, residing at Detroit, Michigan, have invented certain new and useful Improvements in Methods and Machines for Making Radiator-Tubes, of which the following is a full, clear, and exact description.

My invention relates more particularly to method and machines for making radiator tubes of the type described in United States Patent No. 682,649 and its principal object is to improve on the method and machines described in United States Patents, Nos. 777,817, 817,938 and 817,939. Among the improvements effected are the following:

The surface of the tube is well cleaned and a film of flux applied thereon immediately before the corrugated fin is wound upon it. This promotes capillary attraction and causes the flux which is carried onto the tube by the wire of solder to instantly flow to the fin. I provide a jet of air to remove superfluous solder. A coupling is provided for attaching a fresh length of tube to the one nearly completed. This coupling is placed inside of the tubes, whose ends may then be brought into contact and enables winding of the fin to continue without interruption across the joint. After the winding is well started on the new length the fin is cut at the joint and the finished length removed from the machine. Then the carriage is brought back, the chuck attached to the new tube and the process is continued. By this method the entire length of tube is usable, effecting economy of material and saving the time it would take to attach the ribbon anew to each length of tubing. By means of a lever convenient to the operator the machine may be stopped and started and its speed controlled, and a brake applied when desired. A lever is provided whereby to connect the carriage to and disconnect it from the driving mechanism, enabling it to be quickly returned and the chuck connected to the new length of tube.

Tubing used for this purpose is of rather thin gage and as its weight is considerably increased by the fin which is wound on it, one or more supports are necessary to prevent a long length sagging in the middle. For this purpose I provide suitable sup-

ports and means for temporarily retiring them to allow the carriage to pass. 55

In the accompanying drawings:

Figure 1 is a front elevation of my machine;

Fig. 2 is a plan;

Fig. 3 is an elevation of the right hand end, and;

Fig. 4 is an elevation of the left hand end.

Fig. 5 is a view of the chuck.

Fig. 6 is a view of the coupling.

Similar numerals indicate like parts in the several views.

The base of the machine is composed of a pair of longitudinal steel channels 25 united by transverse members 26. An upright 27 is mounted at the left hand end of the base 70 and an upright 28 is mounted at some distance from the right hand end. These uprights support a stationary rod or rail 29 on the top of which is located a rack 30. A carriage having a frame 31 is mounted to slide on the rail and is kept from rotating thereon by the rack. A shaft 32 is mounted to rotate in bearings on the carriage and this shaft carries a pinion 33 which meshes with the rack 30. A bevel gear 34 is mounted on shaft 32. A feather (not seen) fitting in a groove in the shaft permits longitudinal movement of the gear 34 on the shaft while compelling the pinion 33 and gear 34 to rotate as a unit. A bevel pinion 35 is secured to one end and a gear 36 to the other end of a shaft (not seen) which rotates in a bearing 37 in the carriage. The gear 34 normally meshes with pinion 35. The gear 36 meshes with a pinion 38 secured to a hollow 90 shaft 39, also mounted in the carriage, and a pinion 40 is mounted on the other end of this shaft. Through an intermediate gear, 41, gear 40 drives a pinion 42 mounted on a hollow shaft 43, which shaft terminates in 95 a chuck 44. This chuck is merely an expanding arbor over which the tube slips and is expanded by screwing in a screw 45 having a V shaped point.

A shaft 50 is mounted in bearings in the 100 uprights 27 and 28 and passes through the hollow shaft 39. Shaft 50 has a longitudinal groove and a feather in shaft 39 runs therein, compelling the two shafts to rotate as a unit while allowing relative longitudinal movement. A friction disk 51 is mount-

186

ed on the left hand end of shaft 50, the friction surface of the gear being a flat circular surface beveled at its edge. A transverse power shaft 52 rotates in bearings 53 and is 5 constantly driven by a belt running on a pulley 54. The bearings are supported by rods 55 which pass through bearings in the upright 27, compression springs 56 confined between the upright and a tie bar 57 held in 10 place by nuts on the ends of the rods tend to draw the shaft 52 toward the friction disk 51. A friction wheel 58 is arranged to slide longitudinally on shaft 52 but is rotated therewith by a feather. The pinion 15 has a hub 59 with an annular groove in which a collar 60 is mounted. This collar is connected by a bifurcated link 61 to an arm 62 rigidly secured to a rock shaft 63 which runs to a point within reach of the 20 operator, where a lever is rigidly attached, by means of which the operator can shift the friction wheel to various positions with reference to the disk 51 or shift it entirely off of the disk. A brake block 65 is carried by 25 the link 61 which comes in contact with the periphery of the disk 51 when the lever 64 is thrown to one extreme and enables the operator to stop the machine quickly. Each rod 55 is provided with a collar 66 which 30 limits the movement imparted to it by its spring 56 and the lateral movement of shaft 52 is therefore quite small when the wheel is shifted off of the disk.

At its right hand end shaft 50 carries a 35 bevel gear 70 which meshes with a similar bevel gear 71 mounted upon a shaft 72 rotating in a bearing in a bracket 73 attached to the upright 28. A corrugating roll 74 is mounted on the other end of shaft 72 and 40 meshes with and drives a companion corrugating roll 75. At the beginning of the operation a length of tube is passed through a guide bearing 76, carried by upright 28, and secured to the chuck 44. The end of a 45 metallic ribbon, which has passed through the corrugating rolls, is attached to the tube or chuck by any satisfactory means. The end of a wire composed of solder is also secured to the tube or chuck and the machine 50 is then started, the combined rotary and longitudinal movement of the tube, the latter imparted by the pinion 33 enmeshed with the rack 30, causes the corrugated ribbon to be wound on the tube in spiral form, 55 with the solder wire between its convolutions. This is described in one or more of the patents mentioned above and more detailed description of the operation is unnecessary here.

One or more guid bearings 80 are provided to prevent the tube from sagging when the distance between the chuck and guide 76 becomes considerable. These guides are carried by rods 81 mounted to slide ver-

tically in sockets 82; the movement of the 65 rods is limited by pins 83 carried by the rods and playing in slots 84 in the sockets. Compression springs 85 tend to keep the guides up in effective position. A ramp 86 is carried by the carriage which engages 70 shoulders 87 and temporarily depresses the bearings, the springs returning them to normal position after the carriage has passed. This enables the chuck and parts associated therewith to pass the bearings. 75

Close to the guide 76 a trough 90 is placed in which the length of tube lies as it gradually moves toward the machine. At the end of the trough nearest the machine a felt pad 91 is placed so that the tube lies on it. From 80 time to time liquid flux is poured on this pad and the rotary motion of the tube causes the pad to wipe the tube clean, and at the same time depositing a film of flux upon it. The corrugations in the ribbon are at first 85 symmetrical but become distorted by winding the ribbon on the tube, being deepened and narrowed at the inner edge and nearly, if not quite, obliterated at the outer edge. This reformation of the fin is accompanied 90 by more or less rubbing of the edge against the tube, which cleans the edge and moistens it with flux scraped from the surface of the tube. The solder wire passes through a bath of liquid flux, as described in Patent 95 No. 817,939 above referred to, and carries flux up to the tube. This is best shown in Fig. 4 where the solder wire on its way to the tube passes below a rod 77, shown in dotted lines near the bottom of the tank 78 100 containing liquid flux. The film of flux already on the tube attracts the flux brought up by the wire and it immediately spreads to the ribbon. By this means a sufficient quantity of flux is applied just where it is 105 needed without having to pass the ribbon through a flux bath as was done in the earlier machines. The ribbon remains free from flux except at the edge which is in contact with the tube and the solder does 110 not flow over the surface of the ribbon, or "fin" as it is called after it is on the tube. This improves the appearance of the product, increases its efficiency somewhat, and economizes solder and flux. As in the patent above referred to a gas flame is played upon the tube to fuse the solder and while the solder is fluid a jet of air is blown on the tube from a nozzle 92, which removes the 115 superfluous solder. The drawings show two reels containing solder and two solder wires leading to the tube. One or more wires may be used, according to the size of the wires and the amount of solder required. 120

When winding of the length of tube is 125 nearly completed a new length is coupled to it by means of the coupling shown in Fig. 6 which consists of a double screw 95 the cen-

ter of which is enlarged and provided with holes 96 for a pin to use in turning the screw. Each end of the screw has a V shaped end and screws into an expanding arbor 97. These arbors are arranged to expand by their own resiliency so that when they are within the tube they offer sufficient resistance to rotation therein to enable the screw to be turned to clamp them more firmly within the tube. The arbor is first inserted in the nearly finished length and the screw 95 screwed in tightly. Then the new length is slipped over the other arbor. The tendency for the arbor to grip the inside of the new tube and that of the new tube to resist rotation causes the screw to turn in the arbor and tighten the arbor sufficiently to control the new tube until it reaches the winding point, after which the fin itself insures connection between the tube. When the winding has progressed to a predetermined length on the new tube a trigger carried by the carriage (not seen) strikes the lever 98 of a bell. The operator stops the machine by using lever 64 and with a pair of shears clips the fin at the point where it crosses the joint between the tubes. He then releases the chuck and draws a lever 99 on the carriage toward him. This lever is connected by a link 100 and a bifurcated lever 101 to the hub of gear 34 and drawing lever 99 toward him moves gear 34 out of engagement with pinion 35. The carriage can then be moved to the left far enough to withdraw the chuck from the old tube. Next the operator turns the finished tube by hand sufficiently to release the coupling from the new length, the fact that the coupling has been screwed into the finished length by a pin used in holes 96 insuring the coupling remaining in the finished length. He lays the finished length aside temporarily, moves the carriage up to and connects the chuck to the new length. He then throws the lever 99 toward the back of the machine, which reenmeshes gear 34 with pinion 35, and starts the machine with lever 64. He now has a brief period of leisure during which he removes the coupling from and disposes of the finished tube.

I do not wish to be understood to limit myself to the specific details of means or process here described, as numerous deviations are possible without departing from the spirit or altering the purpose of the invention.

What I claim is as follows:

1. A machine for making radiator tubes, comprising means for supporting and rotating a tube at various velocities, means for winding a fin thereon, means for applying flux and solder, a flame to heat the parts and fuse the solder, and excess solder re-

moving means adjacent to the flame, comprising means for directing a jet of air upon the rotating tube and fin while the solder is fluid. 65

2. A machine for making radiator tubes, comprising means for supporting and rotating a tube, means for winding a fin thereon, means for applying flux and solder, a flame to heat the parts and fuse the solder, and excess solder removing means adjacent to the flame, comprising means for directing 75 a jet of air upon the rotating tube and fin while the solder is fluid.

3. In a machine for making radiator tubes, a stationary rail, a carriage mounted to run thereon, a chuck carried by the carriage, means for simultaneously rotating the chuck and propelling the carriage, a stationary guide through which to feed a ribbon to be wound on a tube secured in the chuck, a bearing to support and guide the 85 tube between the chuck and ribbon guide, said bearing being maintained in effective position by a spring, and a ramp on the carriage whereby said bearing is displaced while the carriage is passing the bearing. 90

4. In a machine for making radiator tubes, a stationary rail, a carriage mounted to run thereon, a chuck carried by the carriage, means for simultaneously rotating the 95 chuck and propelling the carriage along the guide, means for feeding a ribbon through a fixed guide so as to wind it in the form of a spiral on a tube secured in the rotating traveling chuck, a bearing to support and guide the tube between the chuck and ribbon 100 guide, and means for automatically placing said bearing in operative position after the carriage has moved a predetermined distance.

5. A machine for making radiator tubes, comprising means for supporting and rotating a tube, means for winding a metallic ribbon on the tube in spiral form, a flux saturated pad arranged to bear against the rotating tube so as to wipe the tube and 110 deposit thereon a film of flux before the ribbon is wound upon it, and means for supplying solder and applying heat whereby to solder the ribbon to the tube as it is wound thereon. 115

6. A machine for making radiator tubes, comprising means for supporting and rotating a tube, means for winding a metallic ribbon thereon in spiral form, a flux saturated pad arranged to bear against the rotating tube so as to wipe the tube and deposit a film of flux thereon before the ribbon is wound upon it, means for passing a wire of solder through a bath of flux and winding it on the tube between the convolutions of the ribbon. 120

7. In a machine for making radiator tubes, means for supporting and rotating

65. tube, a flux saturated pad arranged to bear against the rotating tube so as to wipe the tube and deposit a film of flux upon it, and means for producing relative movement between the pad and tube parallel to the axis of the tube whereby to similarly treat the entire length of the tube.
66. 8. A machine for making radiator tubes comprising means for supporting and rotating a tube, means for winding a fin thereon, means for applying flux and solder, means for heating the solder to fuse the same, and means adjacent to the flame for directing a jet of air upon the rotating tube and fin while the solder is fluid.
67. 9. A machine for making radiator tubes comprising means for supporting and rotating a tube at various velocities, means for winding a fin on said tube, means for applying flux and solder, means for heating the solder to fuse the same, and excess solder removing means adjacent to the flame, comprising means for directing a jet of air upon the rotating tube and fin while the solder is fluid.
68. 10. In a machine for making radiator tubes, a carriage for advancing a tube and a member normally providing a support for said tube positioned in the path of said carriage and actuatable by the carriage away from the tube to allow passage of the carriage.
69. 11. In a machine for making radiator tubes, a carriage for advancing a tube, a member normally providing support for said tube positioned in the path of the carriage and actuatable by the latter away from the tube to allow passage of the carriage, and a spring normally acting on the said member in its tube-engaging position.
70. 12. A machine for making radiator tubes comprising a chuck carried by the carriage, means for simultaneously rotating the chuck and propelling the carriage, means for feeding a ribbon through a fixed guide so as to wind said ribbon spirally on a tube engaging said chuck, and a bearing normally engaging said tube intermediate the guide and chuck, said bearing being actuated by the carriage to allow passage of the latter.
71. 13. A machine for making radiator tubes comprising means for rotating and supporting a tube, means for winding a metallic ribbon spirally upon the tube, means for applying flux to the rotating tube prior to engagement thereof by the ribbon, and means for applying solder to the tube to secure the ribbon thereto, and for the time said solder to fuse the same.
72. 14. A machine for making radiator tubes, comprising means for supporting and rotating a tube, means for winding a metallic ribbon on the tube spirally, means for applying flux to the tube prior to engagement thereof by said ribbon, and means for passing a wire of solder through a bath of flux and winding said wire on the tube between the convolutions of said ribbon.
73. 15. In a machine for making radiator tubes, means for supporting and rotating a tube, means for applying flux to said tube, means for producing relative movement of said tube and the means applying flux parallel to the axis of the tube whereby to similarly treat the entire length of the tube.
74. 16. The method of making radiator tubes comprising the driving of a tube section to spirally wind a fin thereon, securing the fin to the tube during the winding operation, coupling another tube section to that being driven to drive the same thereby before the completion of the winding on the first section and continuing the winding across the junction of the two sections, subsequently severing the fin at the junction, removing the first section and continuing to drive the second section by the wound portion thereof.
75. 17. The method of making radiator tubes comprising the driving of a tube section to spirally wind a fin thereon, successively coupling the tube section to the driven section and continuing the winding of the fin across the junction and upon the coupled section, securing the fin to the tube section while being wound and successively severing the fin at the junction between sections and removing the wound section, whereby the process may be carried on continuously.
76. 18. In a machine for making radiator tubes, the combination with means for rotating and longitudinally advancing a tube, co-operating means for spirally winding a fin upon said tube and securing the same, and means for interiorly coupling another tube section to that being driven in alignment therewith, whereby said fin may be wound continuously from one tube onto another.
77. 19. In a machine for making radiator tubes, the combination with means for rotating and longitudinally advancing a tube, co-operating means for winding and securing a fin thereupon, and a coupler for connecting another tube section, utilizing the relative rotation of said tubes to operate the same and establish driving engagement therebetween.
78. 20. In a machine for making radiator tubes, the combination with means for supporting and rotating a tube and feeding said tube longitudinally, of means for winding and progressively securing a fin thereupon, a coupling member for connecting successive tubes to be wound, comprising expandible clamping elements insertible in said tubes, and a connecting screw-threaded member for expanding said clamping members by relative rotation of the tubes.
79. 21. In a machine for making radiator

tubes, the combination with means for supporting and rotating a tube and feeding said tube longitudinally, of means for winding and progressively securing a fin thereupon, means for coupling another tube section to that being wound comprising expansible tubular clamping members insertible in the adjoining extremities of the tubes, and a connecting member having its end portions insertible in said clamping members to expand the same. 10

In testimony whereof I here affix my signature.

CHARLES A. ELIGH.
